Primary Examiner — Brett Miller*(74) Attorney, Agent, or Firm* — David G. Woodral; GableGotwals(57) **CLAIM**

The ornamental design for a grill, as shown and described.

DESCRIPTION

FIG. 1 is a left front perspective view of the grill of the invention.

FIG. 2 is a front elevational view of the grill of the invention.

FIG. 3 is a rear elevational view of the grill of the invention.

FIG. 4 is a left elevational view of the grill of the invention.

FIG. 5 is a right elevational view of the grill of the invention.

FIG. 6 is a superior view of the grill of the invention; and,

FIG. 7 is an inferior view of the grill of the invention.

The broken lines depict portions of the grill that form no part of the claim.

1 Claim, 6 Drawing Sheets(56)
